UNITED STATES PATENT OFFICE.

OSCAR WHITE, OF ST. LOUIS, MISSOURI.

LIQUID-FUEL BURNER.

Application filed May 4, 1926. Serial No. 106,759.

The invention relates to improvements in burners of the general type in which liquid fuel is volatilized, mixed with air and discharged through perforations.

5 It is the principal object of the present invention to provide a new and improved form of burner particularly adapted for use in connection with cook stoves and ranges, and so constructed that it will be exceptionally 10 simple and inexpensive, yet will be efficient and in every way desirable.

With the foregoing in view, the invention resides in the novel subject matter hereinafter described and claimed, the description 15 being supplemented by the accompanying drawing.

Figure 1 is a top plan view partly broken away and in section, showing the application of the invention to a cook stove.

20 Figure 2 is a front elevation partly broken away and in section.

Figure 3 is a top plan view of the burner partly broken away and in horizontal section.

25 Figures 4 and 5 are transverse sectional views on the correspondingly numbered lines of Fig. 3.

Figure 6 is a central longitudinal section on the plane of line 6—6 of Fig. 5.

30 In the drawings above briefly described, illustrating the preferred form of construction, 7 designates a horizontally elongated hollow body which is preferably of cylindrical form, the upper portion of said body 35 being formed with a multiplicity of perforations 8 while the lower portion of this body is provided with a drip collecting and pre-heating trough 9, said trough being preferably formed by providing the body with a 40 continuous outstanding flange integral therewith. Any desired number of openings 10 may be provided from the interior to the exterior of the body 7, substantially flush with the bottom 11 of said body, for the 45 purpose of permitting the outflow of fuel into the trough 9, for pre-heating purposes. (See Fig. 6).

50 Preferably the body 7 is horizontally divided as indicated at 12, providing it with an upper section 13 which may readily be removed for cleaning purposes, said section then giving access to parts within the body for 55 cleaning them also. The lower section of the body 7 is by preference provided with suitable integral supports 14, and an air supply manifold 15 which extends longitudinally below

the body, may well be integrally connected with one of these supports. This manifold, in the present disclosure, is provided with a plurality of upstanding branches 16 which 60 open through the bottom 11 at longitudinally spaced points, and to prevent the outflow of fuel through these branches, said bottom is provided around them, with upstanding 65 ridges 17.

A perforated fuel pipe 18 is mounted longitudinally within the central portion of the body 7, said pipe being preferably supported upon suitable saddles 19 formed integrally with the bottom 11. A fuel line 20 leads 70 to the pipe 18, preferably from an elevated tank 21 and this line may be provided both with a cutoff valve 22 and with a flow-control valve 23. To overcome the possibility of any oil from the pipe 18, running into 75 the manifold 15, through its branches 16, suitable shields 24 are preferably provided over said branches. These shields may well contact with the lower side of the pipe 18, some of them may be secured directly to this pipe as indicated at 25, while another may be supported on a portion of the fuel line 20, by a nut or the like 26.

In operation, the valve 22 is opened to 80 permit the discharge of oil from the pipe 18 into the body 7, until a sufficient quantity of such oil has entered the trough 9 through the openings 10 for pre-heating purposes. The fuel is then ignited in the trough and by 85 the time it is consumed, the body 7 has been 90 sufficiently heated to effect vaporization of the fuel when the supply is again turned on. Consequently, upon opening of the valve 22, the discharge of fuel from the pipe 18, 95 strikes the hot metal, becomes immediately 95 gasified, mixes thoroughly with air entering through the manifold 15, and discharges through the perforations 8 to produce a hot flame. The intensity of this flame is of 100 course to be controlled by regulation of the valve 23.

Whenever cleaning of the burner is necessary, the valve 22 may be closed and the upper section 13 of the body 7 detached. Then, not only can this section be readily 105 cleaned, but access is had to the pipe 18 and associated parts, so that they also may be effectively freed of any foreign accumulation.

The invention, it will be observed, is exceptionally simple and inexpensive, yet will be sufficient, reliable and in every way desir-

able. On account of the advantages existing for the details disclosed, they are preferably followed. However, within the scope of the invention as claimed, it will be understood that variations may be made. For instance, instead of having the burner body and contained fuel pipe of straight form, they might well be of other shapes, such as that shown in my companion U. S. application Ser. No. 10 106,760, filed May 4, 1926.

I claim:

1. A liquid fuel burner comprising a horizontally elongated hollow tube-like body having a perforated upper portion and having its lower portion provided with an outstanding drip and pre-heating trough, said body having one or more perforations near its bottom for discharging fuel into said trough for pre-heating purposes, a perforated fuel pipe mounted in and extending longitudinally of said body above its bottom, fuel supply means leading to said pipe, air inlet means through the bottom of said body, and guard means around said air inlet means to prevent outflow of fuel therethrough.

2. A liquid fuel burner comprising a horizontally elongated hollow tube-like body having a perforated upper portion and hav-

ing its lower portion provided with an outstanding drip and pre-heating trough, said body having one or more perforations near its bottom for discharging fuel into said trough for pre-heating purposes, a perforated fuel pipe mounted in and extending longitudinally of said body above its bottom, fuel supply means leading to said pipe, and an air supply manifold under said body having upstanding branches discharging at spaced points through the bottom of said body, said bottom having ridges around said branches to prevent outflow of fuel therethrough.

3. A structure as specified in claim 1; said body being horizontally divided to provide an upper section removable for cleaning purposes, said trough being formed by a continuous flange integral with the lower section of the body.

4. A structure as specified in claim 2; together with guards supported at the lower side of said fuel pipe and extending over said branches to prevent descent of oil into said branches from said pipe.

In testimony whereof I have hereunto affixed my signature.

OSCAR WHITE.
